(57) **CLAIM**

The ornamental design for an upper heat insulating cylinder for manufacturing semiconductor wafers, as shown and described.

DESCRIPTION

FIG. 1 is a perspective view of the design for an upper heat insulating cylinder for manufacturing semiconductor wafers in accordance with the invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another top view thereof which shows sectional line 9—9;

FIG. 9 is a sectional view thereof along line 9—9 of FIG. 8; and,

FIG. 10 shows an upper heat insulating cylinder for manufacturing semiconductor wafers in accordance with the invention in use wherein the broken line showing of the environment is for illustrative purpose only and forms no part of the claimed design.
